UNITED STATES PATENT OFFICE.

FREDERICK B. RICE, OF DUNKIRK, NEW YORK.

VALVE-GEAR FOR ENGINES.

SPECIFICATION forming part of Letters Patent No. 245,017, dated August 2, 1881.

Application filed September 17, 1880. (No model.)

To all whom it may concern :

Be it known that I, FREDERICK B. RICE, a citizen of the United States, residing in Dunkirk, in the county of Chautauqua and State of New York, have invented certain new and useful Improvements in Valve-Gears for Engines, of which the following is a specification.

My invention relates to the means for automatically operating the valve of an engine to adapt it to varying loads; and it consists of a rock-shaft arranged to pass through the crank-pin, and having an arm provided with an eccentric-pin for connecting with the valve-rod, in combination with a governor arranged within the crank-disk, as will be more clearly hereinafter shown by reference to the drawings, in which—

Figure 1 is a back view of an engine-crank disk, showing a similar view of a suitable governor for operating my invention. Fig. 2 represents a vertical section in line X X, through the crank-disk; also, a section through a portion of the eccentric-pin arm and through the end of the eccentric-pin connecting-arm. Fig. 3 is a front view of the eccentric-pin arm; and Fig. 4 represents a plan or top view of an engine having my improved device connected thereto.

A represents the crank-disk of an engine; B B', the governor-weights, connected in any well-known way to the arms C C', which arms are pivoted to the disk A, by bolts D D', so as to swing easily thereon.

E represents an arm, pivoted at one end by a bolt, E', to the arm C', and at the other end to a triangular-shaped plate, F, by a bolt, F'. The opposite arm, C, is composed of the parts C C². To the part C² is pivoted, by a bolt, G, a short arm, G', having its opposite end pivoted 40 to the plate F by a bolt, H.

To the plate F is rigidly fastened, in any suitable way, by a nut, H', for instance, a pin, I, which passes through the crank-pin I'. (See Fig. 2.) To the opposite end of the pin I is rigidly fastened an arm, J, which carries the eccentric-pin J', to which pin J' the valve-stem or connecting-rod K is connected in any well-known way. (See Fig. 4, in which a suitable arrangement is shown, representing a plan

view of an engine, L being the fly-wheel and L' the frame.)

M in all the figures represents the crank-shaft or a portion of it. The crank-disk is formed with a depression to receive the governor and a counter-weight, A', to balance it, 55 but may be made in any other well-known form. It will be seen that by this arrangement the governor is placed within the crank-disk of the engine in any suitable form, and operates upon the cut-off valve, and is connected to it through and by a pin which is fitted to a hole bored lengthwise through the crank-pin of the engine, the governor being attached to the inside end of this pin, and a return crank or arm being attached to the outside end, which, in turn, carries a pin for driving the valve, and which takes place of the eccentric. This arm and pin, connected to the valve by an ordinary connecting-rod, are practically like such devices heretofore used, except that the arm is not attached to the engine-crank pin rigidly, but to an inner pin which is loose within the crank-pin, the object of which is plainly manifest, viz., to vary the throw and angular advance of the eccentric-pin, and thereby the travel of the valve automatically, to suit varying loads upon the engine. I claim that this arrangement greatly simplifies automatic cut-offs of this nature.

In cut-offs of this kind heretofore used the 80 governor is generally placed within a wheel or case especially built and placed upon the shaft back of the main bearing, and operates upon an eccentric which is moved either directly across the shaft or around its circumference, the disadvantages of which are obvious. In mine the eccentric is dispensed with, greatly reducing the friction to be overcome by the governor, and first cost, beside making a handsomer and more convenient engine. It 85 operates either main or cut-off valve.

The operation of my invention will be readily understood by reference to Fig. 1. When the centrifugal force resulting from the speed of the engine is sufficient to move the weights 95 B B' in the direction of the arrows f, the outer end of the short arm C² will move in the direction of the arrow h and the arm E in the

direction of the arrow *g*, and will thereby turn the plate *F* and pin *I* in the direction of the arrow *i*, which operation will move the arm *J* and eccentric-pin *J'* in a direction from the dotted lines *s* toward the center of the shaft *M*, or toward the dotted line *s'*, thereby shortening the throw of the valve, or vice versa. The points *r r'* show the extreme movement of the arm *J* in either direction.

10 I claim as my invention—

A moving eccentric-pin, *J'*, arm *J*, pin or rock-shaft *I*, carried by and within an opening through the crank-disk or a crank-pin, *I'*, in combination with a governor arranged within said disk, substantially as specified.

FREDERICK B. RICE.
